UNITED STATES PATENT OFFICE

EDWARD J. ABBOTT, OF WILTON, NEW HAMPSHIRE, ASSIGNOR TO ABBOTT MACHINE COMPANY, OF WILTON, NEW HAMPSHIRE, A CORPORATION OF NEW HAMPSHIRE

KNOT TYING

Application filed August 16, 1930. Serial No. 475,665.

This invention relates to knot tying and has for its principal object to provide an improved art or method of, and devices for, forming knots having relatively long tails. Another object of the invention is to provide a knot tying device capable of ready interchangeability to produce either long or short-tailed knots.

The present invention, although capable of application to knot tying devices, actuated either by hand or by automatic mechanism, will for the purposes of explanation be illustrated and described as embodied in a hand operated knot tying implement of the general type disclosed in United States Patents 672,635, 672,636 and 755,110. Devices exemplifying the present invention may be used for example in tying two strands or filaments together intermediate the ends of the strands and severing the surplus material while yet providing the formed knot with tails sufficiently long to be readily detected later. As applied to weaving for example, the formation of such long-tailed knots permits the weaver to find the knots in woven fabric so that he may pull them all out to one side of the fabric, whereas short-tailed knots previously employed are difficult or almost impossible to locate and hence often necessitate finishing both sides of the fabric.

Other objects of invention, advantage and structural improvements will be apparent from a specific instance of the invention explained by way of example in this specification and its drawings.

In the accompanying drawings:

Fig. 1 is a side elevation of a knot tying device;

Fig. 2 is a plan of the device shown in Fig. 1;

Fig. 3 is a perspective view of the cam shown in Figs. 1 and 2;

Fig. 4 is a section on the line 4—4 of Fig. 3;

Fig. 5 is a detailed view of the stationary guide shown in Figs. 1 and 2, showing the general construction of this guide and the manner in which it is mounted upon the cam cylinder;

Fig. 6 is a perspective view of the loop-

holding finger and of the arm which carries the same;

Fig. 7 includes a plan and a front elevation showing the position of the tying-bill and of the guides just previous to the beginning of the operations which result in the formation of the knot;

Fig. 8 is similar to Fig. 7, but shows the relative arrangement of the parts after the tying-bill has been rotated in a counterclockwise direction for approximately one-third of a revolution;

Fig. 9 is similar to Figs. 7 and 8 and shows the relative arrangement of the parts after the tying-bill has advanced another 90° from the position in which it is shown in Fig. 8;

Fig. 10 is similar to Figs. 7, 8 and 9 and shows the relation of the parts after the tying-bill has advanced approximately 90° from the position shown in Fig. 9;

Fig. 11 is a plan showing the relative arrangement after the tying-bill has advanced approximately 90° from the position shown in Fig. 10; and

Fig. 12 is a view similar to Fig. 11 showing the position of the tying-bill after the knot has been formed and the loop-holding finger removed, so that the knot is ready to be pulled tight.

The instrument shown in Figs. 1 and 2 comprises knot forming and tying mechanism, indicated generally at 10, mounted upon a frame 11 which is provided with a supporting handle 12 and an operating lever 13. A supporting handle 12 for the device may conveniently be provided with a strap 14 adapted to be buckled about the hand of an operator. The operating lever 13, preferably arranged for convenient engagement by the thumb of the hand which carries the instrument, serves to operate a sector cam gear 16, mounted to pivot about the gearing 17 carried by the frame, so that the downward movement of the lever 13 will move the sector cam gear 16 in a clockwise direction as viewed in Fig. 1 or to the right as viewed in Fig. 2. Such downward movement of the lever 13 operates through the sector cam gear 16 and a cooperating gear 31 (Fig. 2) to rotate a shaft 30 and thereby actuate knot-forming and

strand-severing devices which are herein shown as embodied in a tying-bill 32, of conventional form and including a clamping and shearing plate 34 pivotally mounted within 5 the tying-bill. The shaft for the tying-bill extends through a cam cylinder 33 in eccentric position with respect to this cylinder, so that the clamping and shearing plate 34, which is pivotally mounted within the tying- 10 bill and has operative engagement with an interior cam surface of the cam cylinder 33, may operate in the manner well understood in the art to perform its function of clamping the strands and severing the strands closely 15 adjacent to the clamped portion, later releasing the severed ends of the strands after the knot has been pulled tight.

Movement of the sector cam gear 16 by lever 13 also serves to actuate strand-clamping and tightening devices herein shown as comprising a guide arm 24 with a hook-shaped strand-engaging portion 23 at its forward end, arm 24 being pivotally mounted at 19 by means of a transversely extending arm 25 24^a (Fig. 2), and cooperating clamping fingers or plates 22 which loosely embrace opposite sides of the guide arm 24 and are carried by a reciprocating and oscillating arm 21 shown most clearly in Fig. 1. To effect such 20 actuation, a crank having offset arms 18^a and 18^b (Fig. 2) is preferably pivotally mounted at 19 and is provided with a depending cam follower pin 18^c engaging the sector cam gear 16, and a depending pin 18^d upon which the 25 arm 21 is pivotally mounted. This arrangement of parts causes oscillation of the sector cam gear 16 to advance arm 21 to the right from the position of Fig. 1 so that the plates or fingers 22 securely clamp strands which lie 30 within the hook-shaped end 23 of guide arm 24. This movement is effected by movement of the sector cam gear 16 to about its half-way point of oscillating movement, that is to 35 about the point of maximum throw of its 40 arm 21. At such point a spring pressed latch 26 carried by guide arm 24 engages with a pin 27 carried by the arm 18^a so that subsequent return movement of arm 18^a by the 45 sector cam gear will swing arms 24^a and 24^b in a counterclockwise direction (as viewed in Fig. 2) about pivot point 19. Since the 50 clamping plates or fingers 22 embrace arm 24, these parts and the arm 21 will accompany arm 24^a in its counterclockwise movement, the effect of such movement being to pull the 55 strands which have previously been clamped as described above. Upon movement of the 60 crank arm 18^a almost to the end of its stroke a pin 28^a depending from the latch 26 engages a fixed pin 28^b to trip the latch, whereupon a coil spring 28 which bears against both 65 of arms 18^a and 24^a separates these arms and thereby returns the guide arm 24 and the 70 clamping fingers or plates 22 to their initial 75 positions of Figs. 1 and 2.

The apparatus thus far explained, and which is more explicitly described in United States patents numbered 672,635, 672,636 and 755,110 is when taken alone, an example of numerous types of devices suitable for forming 70 knots having very short tails. The unavoidable shortness of the tails will readily be understood from a consideration of the close physical relation of the shearing plate 34 to a loop of strands which would ordinarily 75 form tightly about the tying-bill.

My invention, however, provides a novel mode of operation wherein strand handling instrumentalities are enabled to provide a formed knot at such distance from the strand-severing means as to produce a knot having long tails. To this end, means are provided for preventing the tightening of the formed loop closely about the tying-bill or analogous knot-forming and strand-severing devices, 85 and for determining the point of tightening of the knot at a distance from the strand-severing device, the loop formed by the bill is prevented from diminishing to the relatively small size of the bill by tightening action 90 until after leaving the bill. The loop is therefore of larger size than the usual bill alone could form, and the increased size of the loop is utilized to form knot tails materially longer than would result from merely stripping 95 from the bill a loop formed and tightened closely thereon. In the illustrated embodiment of the invention, structure for performing this function comprises by way of example a loop holding finger 36 carried by the 100 forward end of an arm 37 which preferably, as in the present device, receives its operating movement from the previously described arm 21 by being pivotally mounted thereon by a screw 37^a as shown in Fig. 1. Preferably 105 the arm 37 is affixed to a block 38 which is slotted at 39 (Fig. 6) to fit over the arm 21, and has a transverse hole 41 adapted to receive the pivot screw 37^a.

The forward end of the arm 37 is curved 110 inwardly toward the tying-bill, and the finger 36 extends upwardly from this arm in close proximity with the shank of the tying-bill, so that when the parts are in the position shown in Fig. 7 the inwardly curved portion of the 115 arm 37, together with the finger 36, will serve to retain the strands in engagement with the finger during counterclockwise movement of the tying-bill. Cooperating with the movable guide 23, the finger 36 and the tying-bill, and to hold the strands in the 120 proper position with respect to these parts, I prefer to provide a stationary guide 42 (Fig. 5) mounted upon the cam cylinder 33 in the usual manner, but having a hooked end 43 125 which extends back to a point in rear of the position occupied by the loop-holding finger 36, so that to position the strands in this hook the operator must lay the strands in 130 rear of the upstanding finger 36 as well as 135

in rear of the tying-bill. The upper surface of the hook 43 preferably is higher than the upper end of the finger 36 to avoid the possibility of the strands catching upon this finger during the passage of strands rearwardly over hook 43 in threading the device.

For the purpose of preventing premature pivotal movement of the arm 37 and finger 36, during the forward movement of the arm 21 without interfering with lateral or oscillatory movement which is later imparted to arm 37, a stud 46 is preferably provided upon the frame 11 in position to support the arm 37 during its forward movement. The arm 37 is further restrained from downward movement about the screw 37^a by a spring 47, (Fig. 1) coiled about the shank of the screw 37^a with one end passing through a vertical hole 48 in the arm 21 and turned under the lower side of this arm, and with the other end secured in a recess 49 in the block 38, (Fig. 6), the spring thus being capable of returning arm 37 to its original horizontal level after displacement therefrom.

The functions of the finger 36 of arm 37 and its operative relation to the knot-forming and strand-severing devices and the strand-clamping and tightening devices will be explained with particular reference to Figs. 7 to 12. Attention is directed to the showing in each of these figures of a pair of strands to be knotted, the two strands being distinguished by being shown as white and black respectively.

In Fig. 7, the two strands, having been suitably guided by the guides 43 and 24 and before actuation of the device, are in a position overlying the shank of the trying-bill and intersecting the path of rotation subsequently to be swept by the end of the bill. The initial relation of the finger 36 to the strands and tying-bill is such that strands engaged by the bill and carried by the movement of the bill will thereby be looped around the finger 36, the finger thus being included within the loop. A preferable initial location of the finger 36 is shown as defining a projecting angle in the strands between the two guides 42 and 23 closely adjacent to the shank of the bill and slightly in rear thereof, as shown in Fig. 7. Actuation of the device as a whole to rotate the tying-bill through about one-third of a revolution to the position of Fig. 8 serves to draw the strands about the finger 36 and beak of the tying-bill. The concomitant advance of the arm 21 and clamping fingers 22 has at this point very nearly gripped the strands against the guide hook 23. It will be noted that the finger 36 has moved forward to about the vertical plane swept by the extreme tips of the tying-bill.

In Fig. 9 the tying-bill has moved approximately 90° in a counterclockwise direction from the position shown in Fig. 8. Rotation of the bill has slipped the strands from the

beak portion of the tying-bill down around the throat to complete the formation of the loop which, it will be observed, is formed about the loop-holding finger 36 and the shank of the tying-bill 32. During this movement of the tying-bill the internal cam in the cam cylinder 33 has actuated the shearing and clamping jaw 34 to open the latter to receive the strands between this jaw and the tying-bill 32. The loop-holding finger 36 has also moved farther forward to a position more remote from the tying-bill in order to take up sufficient length of strand to form the long tails of the knot. In this and subsequent positions it will be noted that finger 36 prevents the formation of a close loop completely around the shank of the tying-bill. Fingers 22 in this position of Fig. 9 have moved forward a sufficient distance to clamp the strands against the guide 23.

In Fig. 10 the tying-bill has continued its rotation for approximately 90° from the position shown in Fig. 9, and the internal cam in the cam cylinder 33 has actuated the shearing and clamping jaw 34 partially to close the same against the tying-bill, in which position this jaw is about ready to shear the strands and to clamp the sheared ends thereof against the tying-bill. The loop-holding finger 36 has moved forward slightly to a somewhat greater distance from the tying-bill thus increasing the length of strands taken up between finger 36 and the bill. These positions correspond approximately in point of time with the attainment of maximum throw of the sector cam 16, so that subsequent actuation of the device results in interengagement of the latch 26^a and pin 27 to bring about outward swinging of the guide arm 24 together with the arm 21. Such movement carries the finger 36 to the left to the position of Fig. 11 concomitantly with the actuation of the shearing and clamping jaw 34 to cut the strands and grip the ends of the parts carrying the formed loop. In Fig. 11, the tying-bill is shown in the act of throwing off the loop by pulling the severed ends through the loop to form a knot about finger 36. Outward swinging of arm 24 and further rotation of the tying-bill serve to tighten the formed knot.

In Fig. 12 the tying-bill has continued its counterclockwise rotation for approximately another 90° from the position shown in Fig. 11 and continues to hold the severed ends of the strands for pulling the knot tight. In Fig. 12 the movable guide arm has continued its outward movement, while the loop-holding finger has been swung downwardly about its pivot 37^a by virtue of the engagement of a pin 51 (Figs. 1 and 6), movable with arm 37, with a cam 52 which is fast to the frame and having a suitable curved surface 53.

As shown in Fig. 2, this cam 52 for depressing arm 37 is preferably provided with

a lateral extension 56 which may conveniently be fastened to the device by a screw 57. It will be understood, therefore, that a slight continued movement of the guide 24 clamping fingers 22 and tying-bill 32 will pull the knot tight while the arm 37 and finger 36 are held out of the way, after which the internal cam within the cam cylinder 33 will actuate the shearing and clamping jaw 34 to release the tails of the knot. The configuration of the cam 52 is such that after the knot is pulled tight the pin 51 (Fig. 6) will fall into a cut away portion 54 of the cam so that the spring 47 (Fig. 1) is enabled to return the finger 36 to its initial horizontal level. Movement to this point brings the pin 26^a, associated with the latch 26, (Fig. 2) into engagement with the pin 26^b which trips the latch so as to release the movable guide arm 24 from the arm 18 and permit the coil spring 28 to move the guide arm 24 and clamping fingers 22 back to the position of Figs. 1 and 2.

Obviously, by removing arm 37, with its finger 36, the device described may be caused to function to tie knots with the usual short tails.

It should be understood that the present disclosure is for the purpose of illustration only and that this invention includes all modifications and equivalents which fall within the scope of the appended claims.

I claim:

1. Apparatus for tying a knot in strands comprising a tying-bill provided with loop-forming and strand-severing means, said bill acting to form a loop of the two strands to be knotted and to conduct severed ends of the two strands through the loop to form a knot, and means for enlarging the loop formed by said bill, said last named means acting to determine the point of knot completion at such a distance from the point of operation of the strand-forming means of the bill as to provide the knot with materially longer tails than would result from merely stripping from such a bill a loop formed and tightened closely thereon.

2. Method of tying a knot which comprises forming a loop of the strands to be tied, pulling out the loop to enlarge the loop, severing the strands and pulling the ends of the looped strand through the loop, and tightening the formed loop at a point removed from the cut ends to produce a knot having long tails.

3. A device for knotting strands comprising loop forming means including an element about which two strands to be knotted are first looped, means for severing and clamping the looped strands, strand tightening means acting to remove the loop from said element while converting the loop into a knot, and means engageable within said loop, while the loop is thus being removed from

said element for determining the point of tightening of the formed knot at such a distance from the point of severance of the strands as to provide the knot with long tails.

4. A device for knotting strands comprising a rotatable tying-bill effective to form a loop of the strands, clamp the strands and sever them and throw off the loop over the severed ends to form a knot, means for receiving the forming knot, and means for pulling the strands to tighten the knot about the knot-receiving means.

5. A device for knotting strands comprising loop forming and strand-severing and clamping devices acting together to form a knot comprised of a loop of two strands capable of being pulled into a tight knot, means for pulling the said loop of strands off the loop-forming device and for tightening the formed knot and means for enlarging said loop during its formation thereby to determine the point of tightening of the formed knot at such a distance from the point of severance of the strands as to provide the knot with long tails.

6. A device for knotting strands comprising a rotatable tying-bill for forming a knot and means cooperating therewith for intercepting the strands as they are looped about the tying-bill, thus to maintain the loop open, and for determining the point of tightening of the knot when the formed knot is thrown off the bill.

7. A device for knotting strands comprising means for forming a loop, means for holding the strands at an end of the loop, means for pulling the strands in a direction to pull the loop off the loop-forming means and over the held portions of the strands to form a knot and subsequently to tighten the formed knot, and means engageable with the strands within the formed knot during tightening, thereby to determine the point of tightening with respect to the point at which the strands are held.

8. In a device for tying strands the combination of a rotatable tying-bill and means for determining the point of knot formation comprising a strand engaging member disposed in position to be included within a loop of strands formed by rotation of the bill and to retain the knot formed by casting off the said loop by the bill.

9. A device of the class described comprising means for forming a loop composed of two strands to be knotted, means for clamping and severing the looped strands, and means for pulling the said loop over the severed and clamped ends of the strands to convert the loop into a knot, means for taking up sufficient length of strands within the thus formed loop to provide for tightening the knot subsequently formed at a sufficient distance from the point of operation of the strand-severing means to furnish relatively

long tails on the knot, and means for drawing the knot tight.

10. A device of the class described comprising means for forming a loop composed of two strands to be knotted, means for enlarging the said loop during the formation thereof, means for holding an end of the loop, means for sliding the loop over the holding means to complete the formation of the knot, 10 and means for drawing the knot tight at a point spaced sufficiently from the said holding means to provide relatively long tails on the knot.

11. In a knot tying device having a rotatable tying-bill adapted to engage strands to form a loop about the bill and to clamp and sever the strands, the combination of a movable loop-retaining finger disposed in position to lie within the loop formed by the bill 20 and means for moving the finger away from the bill to complete the formation of the knot at a point spaced a sufficient distance from the bill to provide relatively long tails on the completed knot.

25. 12. In a knot tying device having a rotatable tying-bill adapted to engage strands to form a loop about the bill, and to clamp and sever the strands, the combination of a finger disposed adjacent to the tying-bill and in 30 position to lie within the loop formed by the tying-bill, and means for moving the finger away from the tying-bill during rotation of the latter for carrying the formed knot away from the tying-bill to provide relatively long 35 tails on the knot.

13. A device of the class described comprising fixed and movable guides, a rotatable tying-bill disposed between the guides for forming a loop of strands and for holding 40 and cutting the strands while permitting the formed loop to slide off the bill to form a knot, clamping means cooperating with the movable guide for pulling the knot tight as it slides off the bill, a finger disposed adjacent 45 the bill and in position to be included within the loop formed by the bill, and means for moving the finger away from the bill during the rotation of the bill to increase the size of the loop and to hold the loop as it slides off 50 the bill and while the thread is being pulled tight, and means for withdrawing the finger after the knot is formed but before it is pulled tight.

55. 14. A device of the class described comprising a movable strand guide, a rotatable tying-bill for forming a loop, cutting the strands and holding the ends of the strands while allowing the loop to slide off the bill to form a knot, clamping means movable 60 across the movable guide for clamping the strands and movable with its associated guide to pull the strands thereby to tighten the knot, a finger disposed adjacent the bill in position to lie within the loop during the formation thereof, said finger being movable

with the clamping means and away from the bill to enlarge the loop and to retain the latter as it slides off the bill to form the knot, and means for withdrawing the finger from the loop before the knot is completely 70 tightened.

15. A device of the class described comprising a movable strand guide, a rotatable tying-bill for forming a loop, cutting the strands and holding the ends of the strands 75 while allowing the loop to slide off the bill to form a knot, clamping means movable across the guide for clamping the strands and movable with the guide to pull the strands thereby to tighten the knot, an arm mounted pivotally with respect to the clamping means, a spring for resisting pivotal movement of the arm, a finger on the arm disposed in position to lie within the loop during the formation thereof, and means for imparting a pivotal motion to the arm for withdrawing the finger from the loop before the latter is completely 85 tightened.

16. An attachment for a knot tying device of the type having knot-forming and knot-tightening instrumentalities wherein the knot-tightening instrumentality moves away from the knot-forming instrumentality to tighten a formed knot, the attachment being for the purpose of causing the device to produce knots having long instead of short tails, the attachment comprising a loop-engaging finger adapted to lie in a position to be included within a loop of the knot during formation of the loop and means for connecting 90 said finger to a part of the knot-tightening instrumentality in such a way that the finger moves in synchronism with the knot tightening instrumentality away from the knot-forming instrumentality so as to enlarge the 95 said loop and to determine the point of tightening of the knot at a distance from the knot-forming instrumentality.

17. A device for knotting strands having therein in combination, a rotary loop forming and casting-off tying bill which includes strand clamping and shearing instrumentalities, and means for preventing the loop formed by the bill from diminishing to the size of the bill, by tightening, until after the 105 loop has left the bill.

18. A device for knotting strands having therein in combination, a rotary loop forming and casting-off tying bill which includes strand clamping and shearing instrumentalities, and means for causing a knot formed by said bill to have long tails, said means including a member positioned, adjacent the bill, to be included within the loop formed by said bill, so as to cause said loop to comprise a 110 greater length of strand material than would be wrapped around the bill alone by its rotation.

19. A device for knotting strands comprising a rotatable tying-bill effective to form a 115

loop of the strands, clamp the strands and sever them and throw off the loop over the severed ends to form a knot, means for receiving the forming knot, means for pulling the strands to tighten the knot about the knot-receiving means, and means for removing the said knot-receiving means from the forming knot before the knot is tightened.

20. A device for knotting strands comprising a rotatable tying-bill for forming a knot and means cooperating therewith for intercepting the strands as they are looped about the tying-bill, thus to maintain the loop open, and means for positioning said intercepting means in relation to the tying-bill for determining the point of tightening of the knot when the formed knot is thrown off the bill.

Signed by me at Milford, N. H., this 8th
20 day of August, 1930.
